Inventor:

CLARENCE C. HERBERT
BY: *Frank D. Nowell*
ATTORNEY

UNITED STATES PATENT OFFICE.

CLARENCE C. HERBERT, OF LINCOLN, NEBRASKA.

ELECTRIC WATER-HEATER.

1,384,719.

Specification of Letters Patent. Patented July 12, 1921.

Application filed August 8, 1919. Serial No. 316,277.

To all whom it may concern:

Be it known that I, CLARENCE C. HERBERT, a citizen of the United States, residing at Lincoln, in the county of Lancaster and State of Nebraska, have invented new and useful Improvements in an Electric Water-Heater, which relates to the doing away with all the unnecessary parts, leaving a product that is very simple, can be used to heat water in any vessel, and is very easily repaired.

This invention relates to new and useful improvements in electric water heaters or sterilizers, and consists of a simple and efficient device of this nature having various details of construction, combination and arrangement of parts which will be herein-after fully described, shown in the accompanying drawings and then specifically defined in the appended claim.

My invention is illustrated in the accompanying drawings which, with the letters of reference marked thereon, form a part of this application, and in which:

25 Figure 1 is a perspective view showing the parts assembled.

Fig. 2 is a view showing the perforated carbon tube.

30 Fig. 3 is a detail perspective of a carbon rod with electrical wire attachment, and

Figs. 4 and 5 are modified forms of the invention.

Reference now being had to the details of the drawings by letter:

35 F designates a carbon tube of cylindrical form, having perforations C therein through which water is permitted to freely circulate.

A small solid carbon rod D has disks A thereon and is adapted to telescope within the tubular member F, as shown in Fig. 1 40 of the drawings. A suitable washer E is fitted over the carbon to hold the disk in place. To one end of the carbon rod D an electric wire B is connected, and a second wire B' is adapted to be connected to the 45 perforated carbon tube F, it being understood that the two carbon members are not in contact with each other.

In Figs. 4 and 5 of the drawings a carbon tube H is provided without perforations in 50 the wall thereof and in which a small carbon tube I is adapted to be inserted, the center of which is closed, while the sides and ends are perforated. The parts are adapted to be wired, rubbered and put together in the same manner as shown in Fig. 1.

In operation, a rubber hose is adapted to be placed over one end of the heater and attached to a water faucet, and as the water 60 passes through the tube the water will circulate through the heater and become heated from contact with the members.

What I claim to be new is:

An electric heater comprising a shell of 65 carbon and a rod of carbon of smaller diameter and inserted therein, and means for spacing the same apart from the shell, said spacing means including disks on the ends of the rod entirely inclosing the ends of 70 the shell, and electrical wires connected to said rod and shell.

CLARENCE C. HERBERT.
